UNITED STATES PATENT OFFICE.

FRANK. M. STEVENS, OF NEW YORK, N. Y., ASSIGNOR TO THE STEVENS
LOCOMOTIVE AND MACHINE COMPANY.

VALVE-OPERATING MECHANISM.

SPECIFICATION forming part of Letters Patent No. 323,606, dated August 4, 1885.

Application filed July 9, 1884. (No model.)

To all whom it may concern:

Be it known that I, FRANK. M. STEVENS, a citizen of the United States, and a resident of the city, county, and State of New York, have 5 invented certain new and useful Improvements in Valve-Operating Mechanisms, of which the following is a specification.

My invention relates to means for operating a valve, whereby its regular reciprocating motion may be accelerated and retarded, and whereby the valve-operating eccentric may be shifted to vary the cut-off or reverse the engine. The novel features of the invention will be fully hereinafter described and defined 15 in the claims.

In the drawings, which serve to illustrate my invention, Figure 1 is a sectional side elevation on line 1 1 in Fig. 2. Fig. 2 is a plan with a part of the expansion-guide broken away. Fig. 3 is a sectional elevation on lines 20 3 3 in Figs. 1 and 2. Fig. 4 is a transverse section on line 4 4 in Figs. 1 and 2. Fig. 5 is a sectional elevation on line 5 5 in Fig. 2. Fig. 6 is a detached view of what I call the 25 "multiplying-lever" and its operating-eccentric. Fig. 7 is a detached side view of the carrier-block, and Fig. 8 a detached view of the disk link or die. Fig. 8^a illustrates a modification that will be described.

Referring now to the first eight figures, A 30 is the shaft driven by the engine. It may or may not be the main shaft.

B is an eccentric mounted on this shaft, the shaft passing loosely through a slot or slotted aperture therein. The eccentric is embraced 35 by two keeper-disks, C C, fixed on the shaft, and it bears on its opposite faces ribs *a a*, which engage corresponding grooves in the inner faces of said disks C, whereby the eccentric 40 is compelled to rotate with said disks and the shaft, but is free to move at right angles to the axis of the shaft, so as to vary the throw or reverse the engine. On one face of the eccentric is a rack, *b*, (seen best in Fig. 3,) and 45 opposite said rack is a slot in one of the disks C, and extending through this slot so as to engage said rack *b* is a toothed segment, D, which is fulcrumed at *c* on a stud fixed to the shaft A. Coupled to an arm on segment D at *d* is a 50 link, *e*, which is coupled at its other end to a clutch, E, which slides on the shaft A, being

splined thereon. By sliding clutch E along said shaft the segment D is caused to shift the eccentric on the shaft and vary its position and throw. This may be effected while the 55 shaft A is revolving, and through the medium of a clutch-fork, F, which engages a groove in clutch, as shown in Fig. 3.

I will now describe the means employed for accelerating and retarding the reciprocating 60 movement imparted to the valve by eccentrics B.

G is the eccentric-rod, the strap G' of which embraces eccentric B. H is what I call the "expansion-guide," 65 which I usually bolt to the engine-frame, (not shown,) but which may be secured to any part and in any way so long as it is immovable. In this guide is mounted to play in keepers a carrier-block, I, to which is coupled the eccentric-rod G. Thus the eccentric B imparts by 70 its rotation a reciprocatory motion to the block I. The method of connecting the rod G to the block I will be described hereinafter.

In the block I is mounted a shaft, J, and on 75 the outer or projecting end of this shaft is fulcrumed loosely what I call a "multiplying-lever," M, in the lower end of which is mounted a sliding block, N, in which turns an eccentric, O, fixed on a shaft, P, mounted rotatively in block I.

On the inner end of shaft P—that is, inside of the expansion-guide H—is fixed a pinion, Q, which meshes with a toothed wheel, R, on shaft J. To this wheel R is secured a pinion, 85 S, which meshes with a fixed rack, T, in or on guide H.

To the upper end of lever M is coupled a valve-rod, U, which is coupled at its other end to any form of valve capable of being reciprocated as a locomotive slide-valve. This valve 90 I have not considered it necessary to show.

It will be seen that when the block I is reciprocated through the medium of eccentric B the lever M is carried along with it, thereby imparting a reciprocating motion to the valve; but this reciprocating motion is modified—that is, either accelerated or retarded—by the vibration of said lever, which is effected by the eccentric O, the gear-wheels, 95 100 and the fixed rack T. The character of these modifications will be governed by the distance

through which the block I travels and the respective sizes of the gear-wheels. I have shown the intermediate R as much longer than the pinion Q; but the relative sizes of 5 the gear-wheels may be varied to suit the circumstances of the case.

It will be obvious that the lever M has but one function—namely, to multiply or magnify the motion imparted by the eccentric O. The 10 use of this lever enables me to employ a smaller eccentric than I otherwise could, and to operate when the axis of the valve stem is considerably above or below the horizontal plane in which the axis of the eccentric plays. 15 This lever, however, performs, otherwise, only the ordinary functions of an eccentric yoke and rod to connect the eccentric to the valve-stem, and thus impart to the valve the reciprocating motion due to rotation of the eccentric, as in all eccentric mechanisms for converting rotary into reciprocating motion. It is obvious, also, that if the eccentric O be given the proper throw it may be coupled to the valve-stem by the usual connection. 20 The shaft J may be fixed in the block I, and the link-disk K and gears R S may rotate on it; or it may be rotative and the gears R S be fixed on it; or the disk K and lever M may be mounted on a stud projecting from block I 25 outwardly, and the gears R S be mounted on another stud projecting inwardly from block I. I employ the construction shown for convenience only.

I will now describe the mode of connecting 30 the eccentric-rod G to the carrier-block I.

It will be obvious that when the eccentric B is rotating, the stem G is constantly shifting from a position parallel with the line of movement of block I to an angular position therewith; and it will also be obvious that when the eccentric is shifted at either end of its stroke, in order to vary its throw or reverse the engine, the same shifting of the rod G will occur. Now, if the rod was coupled directly to block I—as by a wrist or pin—there would be a slight reciprocating movement of said block I independent of the regular reciprocation of said block by the eccentric, and due to this change of angle of the eccentric-rod. This independent movement would be such as to accelerate the movement of said block at certain times, thus destroying its regularity. To avoid this I employ by preference a die, K, which is circular or disk-like, and which fits snugly but rotatively in an eye in the end G'' of rod G. This die is mounted eccentrically on the end of shaft J that projects through lever M. The rod G is slotted, and a fulcrum-pin, L, passes through 55 this slot and is fixed in the block I in the same horizontal plane with the shaft J. This position of the parts is clearly shown in the detached view of block I in Fig. 7. This slot in the rod G permits the necessary longitudinal 60 movement of the rod when the eccentric B is shifted, and the swinging or oscillation of the die K on the shaft J permits of the neces-

sary compensation to prevent any reciprocation of block I other than that due to the rotation of the eccentric or the shifting of the eccentric at other points than at the ends of its stroke. This mechanism performs the same function as a link if one end of it was coupled to shaft J and the other to rod G at a point corresponding to the center of die K. I employ the die in order to get a firm extended bearing. In lieu of this die I might employ the modification illustrated in Fig. 8^a. In this construction the end G'' of rod G is provided with a curved slot, K, which is engaged by 80 the shaft J. The radius of this slot is governed by the amount of longitudinal movement of rod G, due to the maximum angle it makes with the line of travel of block I when the eccentric is set at its maximum throw. The effect of this device is to permit the rod G to vibrate on its fulcrum L without said vibration disturbing block I. 85

In order to keep the die K in place, I provide a washer, K', mounted concentrically on 90 shaft J, so as to lap over the die K, and I prefer to make this washer in one with said die. They might, however, be separate. I also allow the washer on the fulcrum-pin L to extend over the edge of the die K for the same 95 reason. These washers form a lateral bearing for the die on the outside, and the lever K forms a lateral bearing for it on the inside.

I wish it understood that I may employ my means for modifying the reciprocating motion 100 of the valve with any means for producing the reciprocating motion; but I prefer the means shown; and I do not limit myself to a train of gear-wheels such as I have shown. For example, the rack T may, in some instances, be arranged to mesh directly with the pinion Q, and the other wheels be omitted, and the rack T need not, necessarily, be mounted on or in the guide H. The disk or plate K', being merely a washer, may be made separate 110 from K, or even omitted, if other means are provided for keeping K in place. The ribs a a might also be on keepers C, and engage grooves in the eccentric B. 115

I do not claim herein every means for modifying the reciprocating motion of a valve, as other means have been proposed for accomplishing this; nor do I limit myself to the precise construction herein shown, as I may employ any equivalent thereof. 120

Having thus described my invention, I claim—

1. In a valve-operating mechanism, a mechanism for modifying the motion of the valve comprising a carrying-block adapted to be reciprocated by the engine, an eccentric mounted rotatively on said carrying-block, a rack-and-pinion device, substantially as described, whereby the reciprocating motion of the carrying-block imparts rotary motion to the eccentric mounted on the carrying-block, and a connection between the said eccentric and the valve-stem, whereby the reciprocating motion imparted to the valve by the reciprocation of 125 130

the carrying-block is modified by the rotation of the eccentric, substantially as set forth.

2. In a valve-operating mechanism, a mechanism for modifying the reciprocating motion 5 of the valve comprising a carrying-block adapted to be reciprocated by the engine, an eccentric mounted rotatively on said carrying-block, a rack-and-pinion device, substantially as described, for converting reciprocating motion of the carrying-block into rotary motion of said eccentric, and a lever fulcrumed on said carrying-block and constructed to connect the said eccentric to the valve-stem, whereby the motion imparted by said eccentric is magnified or multiplied, substantially 15 as shown and described.

3. In a valve-operating mechanism, the combination of a valve-operating eccentric, its strap, its rod G, fulcrumed at L on the carrying-block, the said carrying-block arranged to reciprocate, as shown, and the mechanism, substantially as described, for coupling said rod G to the carrying-block, whereby the effect of the vibration of the said rod on said block is neutralized, substantially as set forth. 25

4. The combination, with the main shaft A, of the keepers C C, fixed thereon and provided with grooves to receive ribs on the eccentric, the slotted eccentric B, provided with ribs a a, 30 and a rack, b, the segment-rack D, pivoted at e on the shaft and arranged to mesh with rack b through a slot in one of the keepers C, the clutch or sleeve E, splined on the shaft and constructed to receive a fork, F, the said fork

F mounted to slide, as shown, and the link e, 35 connected at one end to rack D at d, and at the other end to clutch E, whereby reciprocation of said sleeve rotates rack D, substantially as shown and described.

5. The mechanism for modifying the reciprocating motion of the valve comprising the carrying-block arranged to play in guides, the oscillating lever M, the eccentric O, and its shaft, the fixed rack T, and the gear-wheel or 40 wheels, whereby rotation is imparted to eccentric O O, all arranged to operate substantially as set forth. 45

6. The combination, with the eccentric B and its rod, of the fulcrum-stud L, the link-disk K, the stud or shaft J, and the carrying-block I, said block being mounted in guides, and all arranged to operate substantially as set forth. 50

7. The combination of the shaft A, the valve-operating eccentric and its slotted rod, the fulcrum-pin L, the link-disk K, the guide H, the carrying-block I, the stud or shaft J, the lever M, fulcrumed on J, the eccentric O and its sliding block and shaft, the fixed rack T, and the gear-wheels Q, R, and S, all arranged 55 to operate substantially as set forth. 60

In witness whereof I have hereunto signed my name in the presence of two subscribing witnesses.
